PRINTING MACHINE

Clayton E. Wyrick, Wyandotte, Mich.

Original application August 29, 1936, Serial No. 98,514. Divided and this application January 3, 1938, Serial No. 183,094

25 Claims. (Cl. 192—127)

This invention relates to printing machines and particularly to such machines for the printing of forms or designs on one or more sheets, strips or webs of paper or the like.

5 It is an object of this invention to provide sheet, strip or web aligning means for such a machine.

It is a further object of this invention to provide aligning means for receiving, from a fan-

10 folded pack, a plurality of superposed webs or sheets, and aligning said webs or sheets, and presenting them to the feeding and printing means of the machine.

15 It is a further object of this invention to provide, in association with such aligning means, control means for the motive means of the machine, whereby to make the operation of the machine dependent upon the continuity of the sheets or webs handled in the machine.

20 It is a further object of this invention to provide such means which will operate to shut down the motive means of the machine immediately upon breakage, or exhaustion, of one or more of the webs or upon encountering a torn or mutilated portion therein.

25 It is a further object of this invention to provide, in such a machine, an aligning chamber and a movable aligning means supporting frame which may be withdrawn from the chamber to facilitate loading of the machine by insertion of a plurality of web ends, through the aligning means and into the web feeding and printing means of the machine.

30 It is a further object of this invention to provide, in a printing machine comprising a lower major frame unit or structure and a plurality of superposed printing frames or units hingedly attached to one another and the lower unit, means in the lower major frame unit for aligning and 35 guiding one or more sheets, strips, or webs of material to be printed, which sheets, strips or webs are each to be threaded through, and printed in, one of the printing frames or units; the guiding and alignment of the sheets, strips or webs insuring that they will follow a true 40 course when fed through the printing mechanism in the respective printing frames or units.

45 These and other objects and advantages will appear from the following description taken in connection with the drawings.

This application is a division of my application Serial No. 98,514, filed August 29, 1936.

In the drawings:

50 Figure 1 is an elevational view of a printing machine constructed according to the principles

of this invention with attached stacker, as seen from the right side of the machine;

Figure 2 is a section taken on the line 2—2 of Figure 1;

5 Figure 3 is a longitudinal central section through the lower frame unit and a single superposed printing unit;

Figure 4 is a section taken on the line 4—4 of Figure 3;

10 Figure 5 is a fragmentary view, partly in section, showing the aligning frame in its extended position;

Figure 6 is a diagrammatic view of the electrical circuit connecting the aligning mechanism, the clutch operating mechanism, and the drive 15 motor;

Figure 7 is a diagrammatic view in side elevation of the clutch operating mechanism, showing the parts in position for continuous operation of the machine;

20 Figure 8 is a diagrammatic view similar to Figure 7, but in top plan;

Figure 9 is a diagrammatic view similar to Figure 7, but showing the parts in position to break 25 the power train; and

Figure 10 is a perspective view of the structure shown in Figure 1, with the stacker omitted, and showing the printing units swung into elevated position above the base unit, certain details of the operative structure having been omitted in 30 the interest of clearness of disclosure.

Referring to the drawings in detail and with reference particularly to Figures 1, 5 and 10, I have shown, as illustrative of my invention, a machine comprising a base frame, generally 35 designated A, which contains the aligning chamber and supports a type plate and three printing units or unit assemblies, generally designated B, the lower of which is pivotally secured at the rear end of the base frame A in a manner which 40 will hereinafter more clearly appear, and each of the other printing units B being pivotally connected in like manner to the printing unit therebelow.

The base unit, or base frame A, is mounted on 45 a table E which is supported on legs F. Rigidly secured to the legs F in spaced relation to the table E is the shelf G, which is adapted to support a stack of fan-folded paper webs to be printed in the machine. Rigidly secured to the under 50 side of the table is the motor H. The printing units B are identical, save for the fact that the first, or lower, printing unit only is equipped with a master print control for controlling the printing operations of the superposed printing units 55

as well as a driving clutch for connecting and disconnecting the machine to the driving means.

Base frame (Figs. 1, 2, 3, 4, 5, 6 and 10)

5 The base frame comprises a pair of longitudinal side plates 1 having a horizontally disposed plate member 2 disposed therebetween and to the longitudinal sides of which they are attached by means of screws 3. Disposed between the side plates 1, 10 spaced from and parallel with the plate member 2, is an aligner supporting plate 4 (Figs. 3 and 4) which, in conjunction with the side plates 1 and plate member 2, form the aligning chamber. Longitudinal rails 1a which are fastened to the 15 inside surfaces of the side plates 1, above and below the plate member 2, provide grooves for receiving the sides of the plate member 2 and retaining it in parallelism with the aligner support plate 4.

20 *Aligning means (Figs. 3, 4, 5 and 6)*

With reference particularly to Figures 3 and 4, it will be seen that the aligner of my invention comprises a framework made up of a pair of side 25 members 5, which are secured together in spaced relation by means of the brace rod 6 rigidly secured therebetween at the forward end of the rail and the plate bracket 7 rigidly secured therebetween at the rear end of the rail. Just forward 30 of the plate bracket 7 and secured between the rails 5 in the same manner as the brace rod 6 is the brace rod 8. Rigidly attached to the forward ends of the respective rails 5 are bracket members 9 which are adapted to support the forward guide 35 rolls 10, 11 and 12 for free rotation. In the aligning chamber, at the left side, is secured to the side plate 1 a conductor plate 13 which is insulated therefrom and which has a plurality of conducting contacts 14 secured to the inner side thereof 40 (Fig. 4). A similar conducting plate 15 having conducting contacts 16 is attached to the right-hand side plate 1 in like manner. Journaled for free rotation and having the end pintles thereof insulated from the respective rails 5 are rear 45 guide rolls 17, 18 and 19 respectively. The right-hand pintles of these rear guide rolls extend outwardly and into contact with the conducting contacts 16 on the conductor plate 15.

Secured rearwardly of each of the rear guide 50 rolls 17, 18 and 19 is a conducting rod 20. Each of these conducting rods is insulated from the rails 5 and has its left end in contact with the conducting contacts 14 of the conductor plates 13. The conductor rods 20 are secured against rotation 55 in the rails 5 by means of set screws. The left-hand conductor plate 13 is connected by means of wire 13a to the solenoid 26 while the conductor plate 15 is connected by means of wire 28 to a solenoid operated switch, generally designated 60 29. See diagram, Fig. 6. Adjustably mounted on each conducting rod 20 by means of clamp 23 is a rear guide roll contactor 22 which, when properly adjusted, will resiliently contact each of the respective rear guide rolls 17, 18 and 19. As will 65 clearly appear from Figure 6, when one lead of a circuit is connected to the conductor plate 13 and the other lead to the conductor plate 15, the path of the circuit through the aligner will be, for instance, from a conductor plate 13 through contacts 14 to the conductor rods 20 and thence through guide roll contactors 22 to the respective rear guide rolls and thence through conducting contacts 16 to the conductor plate 15 and thence to the second circuit lead.

70 75 When paper webs are inserted between the re-

spective rear guide roll contactors 22 and the respective rear guide rolls, these circuits will be opened and this is the normal operation of the circuit in the aligner as the circuits are utilized as a safety means which are adapted, when closed 5 by contact of any one of the rear guide roll contactors 22 with any one of the respective rear guide rolls to cause the power of the machine to be shut off for a reason which will hereinafter clearly appear.

10 Slidably mounted on each of the brace rods 6 and 8 is a pair of members 24 which are adapted to support edge guides 25, which edge guides are provided with suitable apertures so that they will clear the rear guide rolls 17, 18 and 19 and 15 the conductor rods 20. Any number of such apertures may be provided in order to accommodate any desired number of rear guide rolls and conductor rods for increasing the capacity of the machine. A like number of apertures is provided 20 in the rails 5 for the same purpose. The edge guides are pressed inwardly against stop means provided on their supporting members 24 by springs received in a peripheral groove of members 24, the details of which members 24 are 25 clearly shown in Figure 2.

This figure also shows the means by which the members 24 are frictionally supported against axial movement on the respective brace rods. The capacity of the machine may be increased by 30 adding more of these members and a like number of forward guide rolls at the front of the aligner to accommodate added paper webs upon the increase of the capacity of the machine by adding additional printing frames. It will be understood that, when it is desired to operate the machine to feed fewer numbers of webs than is accommodated by its ultimate capacity, the circuit closing of any desired rear guide roll contactor 22 may be prevented by the interposition of a 40 piece of paper between the contactor and the roll with which it cooperates or by suitable adjustment of, or removal of, the contactor from its supporting conducting rod 20.

The above described provision on the edge guide 45 support members 24 of suitable means for resiliently urging the edge guides 25 inwardly prevents misalignment of paper webs traveling therebetween. The edge guides may be adjusted transversely of the aligner by means of the sliding engagement of the members 24 with the respective brace rods, upon which they are mounted. This enables the machine to accommodate webs of widely varying widths. The rails 5 are each provided at their rear ends with antifriction means 55 comprising rollers 27 in order to provide for ease in sliding the aligner into and out of the aligning chamber.

Power wiring (Figs. 4 and 6)

60 As shown diagrammatically in Figure 6, the lefthand conductor plate 13 is connected by means of wire 13a with one terminal of the solenoid 26. The other terminal of the solenoid 26 is connected by means of wire 13b to the terminal 29 and also terminal 31 of the electrical plug block 28. The righthand conductor plate 15 is connected by means of wire 15a to the terminal 34 of tumbler switch 35. The opposite terminal 33 of the tumbler switch 35 is connected 65 by means of wire 36 with the terminal 30 of the plug block 28. A wire 37 connects the terminal 34 of the tumbler switch 35 with the terminal 32 of the plug block 28, which terminal is disposed adjacent the terminal 31. A tumbler 38 of the 70 75

tumbler switch 35 is adapted, as shown, to cooperate with terminals 33 and 34 thereof to open and close a circuit between the terminals 33 and 34. This circuit is open when the switch lever 38a is in the rearward, or open, position, as shown in Figure 1. When the switch lever 38a is in its foremost, or upright, position, the circuit between terminals 33 and 34 is closed by the tumbler 38 of the tumbler switch 35 (Figs. 4 and 6).

5 A plug 41 leading from a suitable source of power has the terminal 39 thereof adapted for engagement with the terminal 29 of the plug block 28, and the terminal 40 thereof adapted for engagement with the terminal 30 of the plug block 28. An electric plug 44 is also adapted for detachable insertion into the plug block 28, and this plug 44 has one terminal 42 thereof engageable with the terminal 32 of the plug block 28 and the other terminal 43 thereof engageable with the 10 terminal 31 of the plug block 28.

15 The drive motor H, as illustrated, is of the four-wire type, and two of the wires are connected to the terminal 42 of the plug 44, while the other two wires thereof are connected to the terminal 25 43 of the plug 44.

20 When the power plug 41 and motor plug 44 are properly inserted in the plug block 28, and when the tumbler 38 of the tumbler switch 35 is closed and the switch lever 38a is in upright or forward position, power from the plug 41 passes, from one side of the source of power through terminal 39, terminal 29, terminal 31, two of the four motor wires, to one motor terminal, through the motor, through the other two motor wires, through terminals 42 and 32, through wires 37, terminal 34, tumbler 38, terminal 33, wire 36, terminal 30 and terminal 40 of the power plug 41 to the other wire of the plug 41 which is connected to the opposite side of the source of power.

25 40 Thus, when the switch 35 is closed and the tumbler 38 provides connection between terminals 33 and 34, both these terminals are energized as are also the terminals 29 and 31. The conductor plate 15 is connected by means of wire 15a with the energized terminal 34, while the conductor plate 13 is connected through wire 13a, solenoid coil 26 and wire 13b with both terminals 29 and 31. Due to electrical connection of conducting rods 20 with the conductor plate 13 and electrical connection of the guide rolls 17, 18 and 19 with the conductor plate 15, electrical connection between conductor plates 13 and 15 depends upon 30 35 electrical connection between one or more of the respective conductor rods 20 and its corresponding guide roll 17, 18 or 19.

30 35 When the webs passing between the respective guide roll contactors 22 and their corresponding guide rolls are continuous, electrical connection between conductor plates 13 and 15 is, therefore, prevented. Immediately upon contact of one of the contactors 22 with its corresponding roll (when the tumbler switch 35 is closed and the tumbler 38 engaging terminals 33 and 34), a stick circuit is completed, which extends from terminal 29, through wire 13b, solenoid 26, wire 13a, conductor plate 13, one of the conductor bars 20, the engaging contactor 22, the corresponding 40 45 engaged guide roll, conductor plate 15 and wire 15a, to energized terminal 34.

40 45 The completion of this stick circuit energizes the solenoid 26 which causes the occurrence of power shut-down in a manner which is hereinafter more clearly explained.

5 Clutch operating mechanism (Figs. 1, 2, 4, 6, 7, 8, 9 and 10).

5 As will be understood from the above description, the solenoid 26 is normally de-energized due to separation of each guide roll contactor 22 from its corresponding guide roll by the paper webs passing therebetween. The means by which energization of the solenoid 26 is made to cause power shut-down is as follows: a lever 45 is pivotally secured in suitable manner by screw 45a to the righthand rail 1 forwardly of the solenoid 26, and this lever has an outwardly directed flange to which is bolted the pivoted end of the solenoid armature 46. The solenoid armature 46 is, of course, thrust or drawn to the left, as seen in the above figures, when the solenoid 26 is energized through engagement of a guide roll contactor 22 with its corresponding guide roll, as pointed out above. Normally, however, the lever 45 is freely swingable about its pivot screw 45a which is secured to the side rail 1.

10 15 The lever 48 is pivotally supported by the screw 49 adjacent the lever 45 and has an out-turned flange 50 at its upper end which is provided with a suitable aperture for attachment of the upper end of the tension spring 51. Secured to the upper end of the lever 48 is a screw 52 similar to the screw 49 and slidably supported by these screws which extend through a pair of spaced oval apertures therein is the plate member 53 which has an out-turned horizontal flange 54 at its lower end, providing a thumb piece for manual actuation thereof and adjacent thereto a vertical flange or extension 55 provided with a suitable aperture in which is secured the lower end of the tension spring 51. The plate 53 has a point 53a at its upper end which is adapted to be engaged, in a manner hereinafter more clearly described, by hook means 122 on a link 121 in the carriage operating mechanism to cause the lever 48 to be 20 25 30 35 40 45 50 55 60 65 70 75 80 85 90 95 100 swung rearwardly or in counterclockwise direction from the position of Figure 7 to the position of Figure 8, as shown in Figure 9.

The lever 48 is provided at its rear side with a step 48a (Figs. 7 and 9) which is adapted to cooperate with the forward end of a lever 56 which is pivotally supported by the screw 57 which is secured to the side rail 1 in the same manner as are the screws 45a and 49. This lever has a thumb piece 58 at its forward end and terminates at the rear in a projection 56a which is adapted to cooperate with the step 48a in the lever 48 in a manner hereinafter more clearly described.

The lever 56 has a downwardly directed portion 56b disposed substantially at right angles to the projection 56a and thumb piece 58, and this portion 56b is provided with a suitable aperture through which extends the screw 59 which is rotatable with respect to the portion 56b and which is screw-threaded secured to the forward end of the link 60. The lever 56 has a stud 56c secured to the inner side thereof and a like stud 49b is provided on the inner side of the lever 48, and a spring 61 extends therebetween, as shown in Figures 7 and 9.

The link 60 has a stud 62 at the inner side thereof, which has one end of the tension spring 63 attached thereto, while the other end of the tension spring 63 is attached to a stud 64 secured to the side rail 1. This spring 63 normally urges or biases the link 60 rearwardly of the machine or to the right, as seen in Figures 7 to 9 inclusive. The rearward or righthand end of the link 60 is provided with an aperture through which extends 75

the screw 65 which is rotatable in the aperture and which is screw-threadedly secured to the lever 66. The lever 66 is rigidly secured, at its lower end, to the pintle member 67, to which is also rigidly secured the roller arm 68 upon which is rotatably mounted the clutch roller 69 which cooperates with flanges 97 and 98 of clutch means, hereinafter described, in such manner that when the roller is engaged with these flange means 10 the operating gear train is broken, because the clutch is open (Fig. 9); and when withdrawn therefrom, as shown in Figure 7, the operative gear train is closed to transmit power to the printing units, as is hereinafter more clearly described.

In order that the machine may operate, the parts are set in the position shown in Figure 7 by thrusting the lever 45 rearwardly or to the right and engaging the flange or projection 55 of the plate 53 therewith by thrusting the plate 53 downwardly. The projection 56a on the lever 56 is disposed in the notch 48a of the lever 48, as also shown in Figure 7. The engagement of this projection 56a with the step 48a retains the lever 56 in substantially horizontal position, as shown in Figure 7, whereby to maintain the link 60 in its forwardmost position, as also shown in Figure 7, against tension of the spring 63. The roller 69 is then withdrawn from engagement with the clutch and the operative gear train is complete or closed, whereby power may be transmitted through the closed clutch means to operate the printing units. As above described, the solenoid 26 is de-energized.

When, upon exhaustion of one or more of the webs passing through the aligning chamber, or upon the interposition of a torn place of a web between contactor 22 and its corresponding guide roll, a circuit is completed between conductor plates 13 and 15 to energize the solenoid 26, the solenoid armature 46 is thrust forwardly or to the left, as seen in Figures 7, 8 and 9, from the position of Figure 7 to that of Figure 9. This causes the lever 45 to be swung in clockwise direction to remove the notch 47 thereof from engagement with the flange or projection 55 on the plate 53. The tension spring 51 is, therefore, permitted to move the plate 53 upwardly with respect to the lever 48 in such manner that the point 53a of the plate 53 will be interposed in the path of the hook means 122 on link 121 in the carriage reciprocating means. During this time, the projection 56a has remained in position in the step 48a in lever 48, whereby the lever 48 has been maintained in upright position.

The position of the parts at this time is the same as is shown in Figure 7, save that the lever 45 has been swung forwardly or in clockwise direction and the spring 51 has moved the plate 53 upwardly on the lever 48. The point 53a of the plate 53 is thus placed in the path of the hook means 122 and upon the next passage of the hook means 122 past the point 53a, engagement of the hook means with the point, as shown in dotted lines in Figure 9, will cause the lever 48 to be swung forwardly, in clockwise direction, to the full line position shown in Figure 9, whereby to release the projection 56a from the step 48a in the lever 48 and permit the tension spring 63 to thrust the link 60 forwardly or to the right, whereby the clutch roller 69 will be engaged with the flange means of the clutch to break the operative gear train and prevent further transmission of power to the printing units.

As engagement of the hook means 122 with

the point 53a of the plate 53 occurs always at a predetermined point in the reciprocation of the carriage of the lower, or first, printing unit, and as the other, superposed printing units, are synchronized therewith, stoppage of each carriage 5 will always take place at a certain point in the cycle of operation thereof in such manner that the printing operation of that particular cycle will have been completed and the carriage will be in the position illustrated in Figure 3. 10

The tumbler switch 35 is operated through the link 60. This is accomplished by means of a plate 70 rigidly secured to the link 60 and provided with a pair of spaced pins 71 disposed forwardly, and rearwardly, respectively, with respect to the switch lever 38a of the tumbler switch 35.

When the parts are in the position illustrated in Figure 7, the tumbler switch lever 38a is in upright position and the switch is closed with 20 the tumbler 38 in engagement with terminals 33 and 34 thereof. The motor operating circuit is closed and, as above explained, the clutch is closed because of the spaced relationship between the clutch and the clutch roller 69. When, as 25 above described, the link 60 is released to engage the clutch roller 69 with the clutch flanges and open the clutch, the engagement of pins 71 with the terminal switch lever 38a opens the switch 35 by removing the tumbler 38 from engagement 30 with the terminals 33 and 34 simultaneously with the opening of the clutch.

It will thus be seen that energization of the solenoid 26 causes the plate 53 to move upwardly into the path of the hook means 122 so that engagement of this hook means therewith will cause simultaneous opening of the motor operating circuit and opening of the clutch means in the operating gear train.

Power train (Fig. 2)

40

The drive motor H is provided with a driving pulley having thereon a belt 72 which also operatively engages a pulley 73. The pulley 73 is rigidly secured by means of the screw 74 to the 45 shaft 75 which is suspended, adjacent one end, for free rotation in the bracket 78 secured to the lower side of the plate member 2 by the bolt means 77. At its opposite end, the shaft is 50 rotatably supported by bracket members 78 and 78a formed integrally with the side plate or rail 1 and one of the members 1a respectively.

Endwise movement of the shaft 75 in its supporting brackets is prevented by means of collars 79 and 80 rigidly attached to the shaft between 55 the brackets. Also rigidly attached to the shaft 75 between the collars 79 and 80 is a gear 81. This gear meshes with a gear 82 which is freely 60 rotatably supported on the pintle 67 which carries the lever 66 and roller arm 68.

Formed integrally with, or rigidly secured to, the gear 82 is a gear 83 which is adapted to mesh with a pinion 84 which is supported for free rotation on the headed pintle bolt 85 rigidly secured to members 1 and 1a. Each member 1 is provided with a suitable enlarged boss provided with a stepped cylindrical recess for supporting a bearing member 86 and also a bushing 87. Rotatably supported by these bearings and bushings is the shaft 88. The shaft 88 is provided with cap 70 screws 89 at its opposite ends which cooperate with the bearing means 86 to retain it for rotation, and against axial movement with respect to the frame of the machine.

Rigidly secured by means of a set screw 91 75

to the shaft 88 is a stationary clutch member 90 having a conical clutch surface at its rear end. Adjacent this stationary clutch member 90 is the clutch sleeve 92 having at its right end a portion 5 complementary to the conical clutch surface of the member 90 and provided with antifriction means 93. This sleeve member 92 is provided with a cylindrical recess 94 which extends from the left end thereof to a point adjacent the right end thereof, and in which is disposed the compression spring 95 which is backed at the left end by the bushing 96, which bushing is rotatable with respect to the shaft 88 and which supports the left end of the sleeve 92. At its left end, the 10 sleeve 92 is provided with a reduced portion terminating in an annular flanged portion 97 having an inclined surface complementary to the surface of one flange of the clutch roller 69 which is adapted to be engaged therewith in a manner 15 which will hereinafter more clearly appear.

Extending axially from the flanged portion 97 are a plurality of pins 98. These pins 98 are adapted for engagement in suitable recesses 99 provided in the flanged portion 101 of the pinion 25 100, which pinion 100 meshes with the pinion 84 and which is supported by an axially extending flange formed integrally with the pinion 102. Disposed between the pinion 100 and the pinion 102 is the antifriction thrust washer 103.

30 Due to engagement of the pins 98 and slots 99, the sleeve 92 and pinion 100 are axially movable with respect to one another, but are non-rotatable with respect to one another. The spring 95, through its engagement with the bushing 96 which abuts the end of the pinion 100, normally exerts sufficient axial thrust to cause operative connection between pinion 100 and pinion 102 through the interposed antifriction washer 103. Normally, therefore, the pinions 100 and 102 rotate together or, in other words, the antifriction washer 103 provides operative connection between pinion 100 and pinion 102.

45 As above explained, the clutch roller 69 is normally withdrawn from engagement with the flange means 97 and 98, as illustrated in Figure 7. When, however, the clutch roller 69 is thrust rearwardly to the position shown in Figure 9, the flanges 97 and 98 are engaged by the grooved surface of the clutch roller 69, whereby these flanges 97 and 98 are urged together. This urging together of the flanges 97 and 98 shortens the effective length of the unit formed by the axially movable sleeve 92 and pinion 100, whereby 50 by pressure exerted through spring 95 upon the antifriction washer 103 and antifriction means 93 is sufficiently reduced to permit the pinion 100, and its non-rotatably connected sleeve 92, to rotate free of the pinion 102. As the drive 55 for the carriage reciprocating mechanism in each of the printing units of the machine is derived from the pinion 102, this disconnection of the pinion 102 from the drive pinion 100 breaks the drive power train.

60 As above explained, rearward movement of the link 60 may occur only at one point in each operative cycle of the machine and, therefore, the connection between the driving pinion 100 and the driven pinion 102 is likewise opened at a 65 particular point in the cycle. Simultaneously, with the opening of the power drive train, as above described, the motor energizing circuit is opened and the disconnection of the power train at this time prevents further operation of the

printing mechanism due to "coasting" of the motor after its energizing circuit is opened.

The frame of each printing unit B comprises a roof plate 104 having secured thereto, and therebelow, by means of bolts 106, a pair of lower side plates 105 and having secured thereto and thereabove by means of screws 108, a pair of upper side plates 107 (Fig. 2). The lower side plates 105 are provided with suitable apertures for receiving roller bearings 86a similar to the 10 above described roller bearings 86, and rotatably supported in each pair of roller bearings 86a is the shaft 109 having rigidly secured at each end thereof a chain sprocket 110 which supports and drives the sprocket chain 111 of 15 each corresponding printing unit.

The shaft 109 of the lower unit B which is pivotally secured by means of bushings 87 to the unit A, is driven by means of the pinion 112 rigidly secured thereto by means of the set 20 screw 113. The pinion 112 constantly meshes with the pinion 102 and is rotated thereby during rotation of the said pinion 102 when the above-described clutch is closed. At its opposite end, the shaft 109 of the lower unit has a pinion 25 114 non-rotatably secured thereto by means of set screw 115. Each shaft 109 of each unit B is provided with such pinion 114.

In order that each unit be secured to the unit therebelow, pivotally, at its rear end, the 30 lower side plates of each upper unit are so spaced as to be disposed within the lower side plates 107 of the unit therebelow and the upper and lower side plates are provided with aligned apertures in which are disposed the pintle members 87a similar to the bushings 87 of the base unit A. These pintle members 87a are rigidly secured in suitable manner to the upper side plates 107. This provides for pivotal connection of the superposed units at their rear ends. In 35 order that drive connection be provided between the sprockets 114 of the superposed units, each roof plate 104 is provided with a suitable aperture across which extends axle means providing free rotatable support for gears 116. 45

As will be seen from the right of Figure 2, rotation of the lower shaft 109 through rotation by pinion 102 of its rigidly secured pinion 112 causes power to be transmitted through its rigidly secured pinion 114 to the gear 116 disposed thereabove and thence to the next pinion 114 thereabove to cause rotation of its rigidly secured supporting shaft 109, thence from the second pinion 114 through the second gear 116 to the sprocket 114 thereabove, whereby to rotate its rigidly secured shaft 109. 50 55

As the sprockets 110 are rigidly secured to opposite ends of the shafts 109, these sprockets drive the supported chains 111 simultaneously, 60 in synchronism and at the same speed. The chains 111, as above explained, are supported at the rear end of the machine by the sprockets 110. The forward ends of the chains are supported by sprockets 117 which are freely rotatable on the outside of the frames, and suitable chain guide means 118 is provided which also adjustably supports the pintle 119 of each rear sprocket 117. 65

Pivottally secured to a link of each chain is 70 an offset bearing member 120 which is rigidly secured to one end of a link 121 which is adapted to translate travel of the chains into reciprocatory movement of the carriages in the printing units. Thus, by rotation of the shafts 109, 75

the carriages of the printing units are caused to reciprocate in synchronism.

Formed at the lower end of the righthand link 121 of the lower printing unit is the hook 122, which extends downwardly and which, as above described, is adapted to engage the point 53a on the plate 53 to cause release of the link 60 for forward movement subsequent to energization of the solenoid 26, as above described. (See Figs. 10 7, 8 and 9).

Printing units (Figs. 1, 2, 3 and 10)

The details of the printing units, the braking means and controls for locking the paper webs 15 to the carriage and releasing them therefrom, as well as the means for moving and controlling the impression roller of the carriage, and as well as the means for adjusting and controlling the ink supply roll of the ink fountain and the means for 20 supporting the printing plate or type plate are fully described in my co-pending application Serial No. 98,514, filed August 29, 1936, of which this application is a division.

As the details of this structure are not, per se, 25 a part of the subject-matter claimed in this application, they will be hereinafter described briefly, rather than in detail. The details of the lower printing unit are shown in section in Figure 3, wherein it will be seen that the printing plate 30 or type plate 123 is removably supported upon the plate 2.

Forwardly of the printing plate is the ink fountain generally designated 124 which is also 35 removably attached to the plate 2. In the superposed units, this structure is supported upon the roof plate 104 of the printing unit therebelow. The ink fountain comprises a tank-like casing having supported therein a pair of engaging rolls 125, the forwardmost of which engages the ink 40 supply roll 126. The roll 126 is caused to rotate a predetermined amount by the movement of the carriage upon its return, or printing, stroke and means is provided for predeterminedly adjusting the amount of rotation of the ink supply roll 126, 45 which will occur upon each traverse of the carriage in a cycle of operation of the machine. The rolls 125 are adapted to supply ink to the ink supply roll 126 and the amount of rotation of the ink supply roll will, therefore, determine the 50 amount of ink supplied by this roll 126 to the ink transfer rolls 143 in each cycle of operation.

Web supporting means (Figs. 2 and 3)

The web is supported at the forward end of 55 each printing unit by the web supporting roller 127 journaled for free rotation between the side plates 105 at the lefthand end of the frame, as shown in Figure 3. Cooperating with this roller are a plurality of resiliently faced brake or clamp 60 members 128 which are rigidly secured to the clamp support shaft 129 which may be rocked to urge the brake or clamp members 128 away from the web supporting roller 127. Resilient means 65 130 normally urges the brake or clamp members 128 toward the web supporting roller 127 and the web supported thereby. When the members 128 engage a web supported on the roller 127, they fixedly secure the web and supporting roller 127 against movement with respect to the machine.

At the rear end of each printing unit, the web is supported by a pair of drive rollers 131 which 70 rotate with the shaft 109 of the unit and which are axially adjustable on the shaft, as shown in Figure 2. A swingable web compression roller

132 cooperates with each pair of drive rollers 131 to clamp the web therebetween, and the web compression roller 132 is supported for free rotation by a pair of arms 133 which are pivotally mounted on the shaft 134 which is rigidly disposed between the side plates 105. Leaf spring means 135, which is adjustable through adjusting screw 136, resiliently urges the web compression roller 133 against the cooperating drive rollers 131.

Clamp or brake members 137 provided with 10 resilient facings similar to those of the members 128 are mounted in such manner as to be disposed beneath the web at its point of engagement with the web compression roller 132 in such manner that, when the clamp or brake members 15 137 are raised, the web is spaced from the drive rollers 131. When the clamp or brake members 137 are moved downwardly out of engagement with the web, the web may be clampingly engaged by means of the web compression roller 20 132 with the drive rollers 131 in such manner that the drive rollers 131 may move it toward the right, as shown in Figure 3.

It will thus be seen that the web is supported 25 at opposite ends by web supporting roller 127 and drive rollers 131 respectively, and that by means of brake or clamp means 128 and 137, it may be held, at certain times, against movement with respect to the printing unit through which it extends.

The carrier assemblies or carriages each comprises a pair of plate-like side members 138 which are secured in rigid spaced relation by means of the L-section plate member 139 rigidly attached at the left upper corners of each side member 35 and the arcuate paper web guide plate 140 arranged centrally between the two side members and rigidly attached at each end thereto. The front axle member 141 is also rigidly locked at each end in the respective side members and supports at each end outwardly of the side plates 138 a roller 141a (Fig. 1) adapted for support on the trackway 105a provided therefor in each side plate 105.

A second or rear axle member 142 is rotatably 45 journaled in the side plates or members 138, and this rear axle member 142 rotatably supports at each end thereof outside the side walls 138 suitable rollers 142a (Fig. 1) adapted for support on the trackway 105. Also secured to the opposite ends of the axles 142 are the upper ends of corresponding links 121, above described, which have their opposite or lower ends secured to the sprocket chains 111. Reciprocation of the carriage is thus accomplished by travel of the 55 sprocket chains 111.

Suitably supported for rotation in the carriage leftwardly of the web guide plate 140 is a pair of resiliently faced ink transfer rolls 143, with which is associated an axially reciprocable ink 60 spreader roll 144 which is provided with axial reciprocating movement during longitudinal reciprocating movement of the carriage in the printing unit. When the carriage, upon its printing or leftward stroke, reaches the end of 65 its travel, the ink transfer rolls 143 engage the ink supply roll 126, whereby to take ink therefrom; and upon the succeeding web moving or rightward movement of the carriage, these ink transfer rolls 143 transfer the ink received from 70 the ink supply roll 126 to the printing surface of the printing plate or type plate 123. Rotatably secured between the side plates 138 substantially directly below the front axle member 141 is the web supporting shaft 145 having thereon 75

non-smear web supporting rollers 146 over which the web passes.

Disposed between the web supporting rollers 146 and the web guide plate 140 is the swingable impression roller 147 which engages the top surface of the web. The movement of this impression roller 147 is so controlled that on the rightward or feeding stroke of the carriage it is disposed in its upward position whereby the web which is progressively engaged thereby remains spaced from the printing surface of the printing plate or type plate 123. Upon the succeeding or opposite printing stroke, the impression roller is disposed in its lowermost position whereby to progressively engage the web, which is then clamped to the printing unit by operation of the brake or clamping members 128 and 137, against the inked printing surface of the printing plate or type plate 123, which has been inked by the ink transfer rolls 143 during the feeding movement of the carriage. In order that the web may be fed, advanced, or moved to the right, as shown in Figure 3, upon the feeding or rightward stroke of the carriage, means is provided for clamping the web to the carriage in order that this may be accomplished.

This means comprises the web support plate 148 which is of bent-up form and which is adapted to engage the folded or serrated portions of the web led thereover, as shown in Figure 3. To the right of the web guide plate 140 is the shaft 149 which has fixed thereto suitable arms 150 having pivotally secured to their free ends the clamping roller supporting links 151, to the free end of which is secured for free rotation the clamping or clasping roller 152.

During the feeding or rightward stroke of the carriage, the clamping or clasping roller 152 is forced into cooperative clamping relation with the web support plate 148 in such manner that the web will be tightly clamped between the clamping or clasping roller 152 and the web support plate 148, whereby rightward or advancing motion of the carriage will cause the web, which is secured thereto, to be advanced toward the right, as seen in Figure 3, for a predetermined amount. When this predetermined advancement has occurred, by means of adjustable control means cooperating with the clamping or clasping roller support, the clamping or clasping roller 152 is moved to the released position shown in Figure 3. By means of other controls provided for the brake or clamping members 128 and 137, these brake means are released when the clamping or clasping roller 152 secures the web to the movable carriage. However, immediately upon release of the clamping or clasping roller 152, as above described, the brakes or clamping members 128 are again applied to secure the web in stationary relation with respect to the machine.

As above stated, the means for controlling the brakes, the clamping or clasping roller 152, etc. is fully described in my copending application Serial No. 98,514, filed August 29, 1936, of which this application is a division. Description of these complicated control means is omitted from this application, as they do not form, per se, a part of the invention covered in this application.

Briefly, the operation of the printing units is as follows. As shown in Figure 3, the parts are in the "at rest" or "starting" position, which is taken when the power train and power circuit have been interrupted, as above described. Upon starting the machine, the carriage will move rightwardly, as seen in Figure 3, and at a prede-

termined time, the clamping or clasping roller 152 will be thrust against the web support plate 148 to clamp the web to the carriage.

Simultaneously, the brake means 128 and 137 will be released, whereby the roller 127 will be freely rotatable to permit advance of the web at that end of the printing unit, while the web will be resiliently urged by the web compression roller 132 against the driven drive rollers 131 at the opposite end. This engagement with the rotating drive rollers will cause the web to be advanced to maintain the web taut. Due to the upward disposition of the impression roller 147, the web will be advanced out of contact with the printing plate or type plate 123 until a predetermined amount of advance or feeding thereof has occurred.

The clamping or clasping roller 152 will then be released to free the web from the carriage, while simultaneously the web will be clamped by the brake or clamping means 128 and 137, which is then applied, and secured against further movement in the frame of the printing unit. The carriage will continue to advance to the right end of the trackway and during the movement of the carriage in this direction, the ink transfer rolls 143 will ink the printing surface of the printing plate or type plate 123. The movement of the carriage is then reversed and, at a predetermined point in its succeeding leftward stroke, the impression roller 147 is caused to move downwardly to progressively present the lower side of the web against the upper or printing surface of the printing plate or type plate 123. Adjacent the end of this printing stroke of the carriage, the impression roller 147 is again moved upwardly, and the ink transfer rolls 143 pass over the ink supply roll 126 of the ink fountain to have ink applied thereto which is thereafter, upon the next feeding stroke of the carriage, applied by the ink transfer rolls 143 to the upper or printing surface of the printing plate or type plate 123.

As above described, the fanfolded webs are supported upon the shelf G and then pass through the aligning chamber, thence through the printing units and, as they issue from the printing units, they pass through suitable guide roller means provided in the web delivery guide generally designated 153, and they are guided thence into the stacker generally designated 154, which stacker is driven from, and in synchronism with, the printing machine. The stacker re-stacks the unfolded webs into superposed fanfolded relation in the manner in which they were folded and supported upon the shelf G before the printing thereof had been accomplished.

The side standards of the web guide 153 are provided with spaced notches which are adapted for engagement with a rod member 87b disposed in apertures provided in the members 107 of the topmost printing unit, and this rod may be engaged in the notches provided in the web delivery guide frame to support the printing units of the machine in tilted relation, as shown in Figure 10, in order to facilitate threading of unprinted webs therethrough in loading the machine.

The separate printing units are pivotal with respect to one another and with respect to the base, and in threading the machine the units are placed in the position shown in Figure 10, whereupon to facilitate threading of the lowermost web through the lowermost printing unit, then the lowermost printing unit is brought downwardly and latchedly secured by latch means 154 to the base unit. The under side of the second

printing unit is then exposed for ease of threading the second unprinted web therethrough, and after this threading has been accomplished, the second unit is brought down into position above the lowermost printing unit and latched thereto by the latch means 154. This procedure is followed in threading the third printing unit and thereafter the third printing unit is latchedly secured to the second printing unit in such manner that the parts take the position illustrated in Figure 1.

As above described, any suitable number of printing units may be provided in the machine due to its built-up construction and the interchangeability of printing units and their equipment, save for the lower printing unit which is provided with certain equipment which is not necessary in the printing units thereabove. All of this construction and the advantages thereof are fully described in my copending application Serial No. 98,514, filed August 29, 1936, of which this application is a division.

It will be understood that the above-described structure is merely illustrative of the manner in which the principles of my invention may be utilized and that I desire to comprehend within my invention such modifications as come within the scope of the claims and the invention.

Having thus fully described my invention, what I claim as new and desire to secure by Letters Patent is:

1. In a printing machine having paper web feeding means and reciprocating printing means, a prime mover, and paper web aligning mechanism, said aligning mechanism having associated means adapted, upon exhaustion of the paper web supply, to automatically initiate the disconnection of said prime mover from said paper feeding and printing means.

2. In a printing machine for paper sheets, paper sheet feeding means and reciprocating printing means, a prime mover for actuating said sheet feeding and printing means, paper sheet aligning mechanism, said paper sheet feeding means being operable through a power train connected to said prime mover, and means associated with said paper sheet aligning means for automatically shutting off said prime mover and opening said power train at a predetermined position upon the discontinuance of paper sheets passing through said printing machine.

3. In a printing machine, paper web feeding means and reciprocating printing means, a prime mover for actuating said paper web feeding means and reciprocating printing means, said paper web feeding means including means adapted, upon exhaustion or discontinuity of said paper web, to simultaneously shut down the prime mover and stop the reciprocation of said printing means at a predetermined position in the operation cycle.

4. In a printing machine, paper web feeding means and reciprocating printing means, a prime mover for actuating said feeding and printing means, said paper feeding means including electrical contact members which are adapted normally to be separated by the paper web and adapted to be responsive to paper discontinuance to initiate the simultaneous shutting down of the prime mover and stopping the reciprocating printing means at a predetermined time.

5. In a printing machine, paper sheet feeding means and reciprocating printing mechanism for printing said sheets as they are moved through said machine, prime mover means for operating

said sheet feeding and printing means, paper sheet aligning mechanism, and means associated with said sheet aligning mechanism which is adapted, upon exhaustion or discontinuance of said paper sheets, to shut down the prime mover 5 and effect the automatic stopping of said reciprocating printing mechanism at the end of its printing operation cycle.

6. In a printing machine, means for feeding a plurality of superimposed paper sheets, means 10 for aligning said plurality of paper sheets, means comprising reciprocable mechanism for printing said sheets as they are moved along through said machine, common prime mover means for operating said feeding means and said printing 15 means, and means associated with said aligning means adapted, upon encountering torn or discontinuous portions of said paper sheets, to effect automatic disconnection of said prime mover from said feeding and printing means and stop- 20 ping of said reciprocable printing mechanism.

7. In a printing machine, separate web feeding and printing means, a prime mover for actuating said feeding and printing means having an electric operating circuit, web aligning means for 25 guiding aligned webs of paper to said feeding and printing means, switch means in said circuit, a gear train drivingly connected to said prime mover and arranged to operate said feeding and printing mechanism, friction clutch means in said 30 gear train, and means associated with said feeding means responsive to paper exhaustion for simultaneously opening said switch and said clutch means to shut off said prime mover and disconnect said gear train to stop said printing 35 machine.

8. In a printing machine having paper web feed means and reciprocating printing means, a prime mover having an electric operating circuit, switch means in said circuit, a feed means and 40 printing means, a driving gear train operatively connected with said prime mover, clutch means in said gear train, and common means responsive to paper web exhaustion for simultaneously operating said switch means and said clutch means 45 to shut off said prime mover and open said gear train at a predetermined subsequent time whereby to stop said web feeding and printing means in a predetermined position in its operative cycle.

9. In a printing machine having web feeding 50 means and reciprocating printing means, a gear train for operating said web feeding means and said printing means, friction clutch means in said gear train, a prime mover drivingly connected with said gear train through said clutch means, 55 and common means responsive to web exhaustion for simultaneously shutting off said prime mover and operating said clutch to open said gear train at a predetermined subsequent time whereby to stop said web feeding and printing 60 means in a predetermined position in its operative cycle.

10. In a printing machine having plural superposed units with web feeding means and printing means therein, a gear train for operating said 65 web feeding means and said printing means in synchronism, friction clutch means in said gear train, a prime mover drivingly connected to said gear train through said clutch means, and common means responsive to web exhaustion for 70 initiating simultaneous shutting off of said prime mover and interruption of said gear train by operation of said clutch under the control of the web feeding means and printing means at a predetermined subsequent time whereby to stop said 75

- web feeding and printing means in a predetermined position in its operative cycle.
11. In a printing machine having common reciprocating means for feeding and printing a paper web, switch controlled motor means, means including a clutch operatively connecting said motor means with said reciprocating feeding and printing means, and means responsive to web exhaustion for automatically initiating simultaneous stoppage of said motor means and opening of said clutch means under the control of said reciprocating feeding and printing means at a predetermined subsequent time whereby to stop said web feeding and printing means in a predetermined position in its operative cycle.
12. In a printing machine having common reciprocating means for feeding and printing paper webs, switch controlled drive motor means, means including a clutch operatively connecting said motor means with said reciprocating feeding and printing means, and means responsive to web exhaustion for automatically initiating stoppage of said motor means and opening of said clutch, and means associated with said reciprocating feeding and printing means for simultaneously opening said motor switch and said clutch means to effect stoppage of said machine at a predetermined point in the operative cycle thereof.
13. In a printing machine having common reciprocating means for feeding and printing a paper web, aligning means for supplying an aligned web to said feeding and printing means, switch controlled drive motor means, means including a clutch operatively connecting said motor means with said feeding and printing means, and means responsive to web exhaustion for automatically initiating simultaneous stoppage of said motor means and opening of said clutch at a predetermined position in the operative cycle.
14. In a printing machine having common reciprocating means for feeding and printing a paper web, web aligning means including guide roll means for supplying an aligned web to said feeding and printing means, switch controlled drive motor means, means including a clutch operatively connecting said motor means with said feeding and printing means, and means responsive to web exhaustion for automatically initiating simultaneous stoppage of said motor means and opening of said clutch, said means including a circuit switch associated with said aligning means and normally held open by passage of the paper web around said web guide roll means.
15. In a printing machine having common reciprocating means for feeding and printing a paper web, aligning means for supplying an aligned web to said feeding and printing means, switch controlled drive motor means, means including a clutch operatively connecting said motor means with said feeding and printing means, and means responsive to web exhaustion for automatically initiating simultaneous stoppage of said motor means and opening of said clutch under the control of said reciprocating feeding and power means at a predetermined position in the operative cycle.
16. In a printing machine having common reciprocating means for feeding and printing a paper web, web aligning mechanism including guide roll means for supplying an aligned web to said feeding and printing means, switch controlled drive motor means, means including a clutch operatively connecting said motor means

with said feeding and printing means, and means associated with said web aligning mechanism responsive to web exhaustion for automatically initiating simultaneous stoppage of said motor means and opening of said clutch, said means including a circuit switch associated with said aligning means and normally held open by passage of the paper web through said aligning means, a solenoid circuit controlled by said circuit switch, and a solenoid operated latch lever moved to unlatching position through completion of said solenoid circuit to make said motor switch and clutch opening means operative through said reciprocating feeding and printing means.

17. In a printing machine, a prime mover, control switch means for starting and stopping said prime mover, clutch means operatively connected to said prime mover, reciprocable paper feeding and printing carriage means operatively connected to said clutch means, and means responsive to lack of continuity of paper for initiating simultaneous opening of said switch means and clutch to stop said prime mover at a predetermined position during the operative cycle.

18. In a printing machine, a prime mover, control switch means for starting and stopping said prime mover, clutch means operatively connected to said prime mover, reciprocable paper web feeding and printing carriage means operatively connected to clutch means, web aligning mechanism including side members and guide roll means for guiding paper webs to said feeding and printing carriage means, and means associated with said aligning mechanism and responsive to lack of continuity of paper webs passing therethrough for initiating simultaneous operation of said switch means and clutch under the control of the reciprocable feeding and printing carriage means to stop said prime mover and open said clutch.

19. In a printing machine, a prime mover having an operating circuit, control switch means for opening said circuit to stop said prime mover, clutch means operatively connected to said prime mover, plural reciprocable web feeding carriage means operatively connected to said clutch means and driven therethrough by said prime mover, aligning means including predeterminedly spaced guide rollers for guiding webs to said web feeding carriage means, and means associated with the guide rollers of said aligning means and responsive to lack of continuity of webs passing therebetween for initiating simultaneous opening of said switch means and said clutch under the control of the position of the reciprocable web feeding carriage means to open the prime mover operating circuit and simultaneously open said clutch to prevent movement of said web feeding carriage means past predetermined points in its operative cycle upon "coasting" of said prime mover after opening of said operating circuit.

20. In a printing machine, a power circuit, a prime mover operated thereby, a gear train operatively connected to said prime mover, a clutch in said gear train, reciprocable paper web feeding and printing carriage means operatively connected to said clutch means, web aligning roller means for supplying aligned paper web to said feeding and printing means, means for simultaneously opening the clutch and power circuit, and means operative during continuity of fed paper webs to latch said clutch and power circuit opening means from operation and operative upon failure of paper web continuity to unlatch said

clutch and power circuit opening means for operation by said paper feeding means.

21. In a printing machine, a power circuit, a prime mover operated thereby, a gear train operatively connected to said prime mover, reciprocating paper web feeding means operatively connected to said gear train, a clutch in said gear train, means for simultaneously opening the clutch and power circuit, web aligning means comprising spaced guide rollers for guiding paper webs to said feeding and printing means, and means operative during continuity of fed paper webs to latch said clutch and power circuit opening means from operation and operative upon failure of paper web continuity to unlatch said clutch and power circuit opening means for operation by said reciprocating paper feeding means.

22. In a printing machine, reciprocating paper feeding means, a prime mover, means including a clutch for operatively connecting said paper feeding means to said prime mover, an electrical circuit operative when completed to initiate simultaneous stoppage of said prime mover and opening of said clutch by said reciprocating paper feeding means, aligning means for guiding paper webs to said feeding and printing means including guide rolls spaced at equal predetermined distances in the path of the paper webs from the corresponding carriage means, and means including electrical contacts cooperating with said guide rolls and normally spaced therefrom by paper webs passing therebetween for completing the circuit to initiate simultaneous stoppage of said prime mover and opening of said clutch upon occurrence of paper exhaustion.

23. In a printing machine, reciprocating paper feeding means, a prime mover, means including a clutch for operatively connecting said paper feeding means to said prime mover, an electrical circuit operative when completed to initiate simultaneous stoppage of said prime mover and opening of said clutch by said reciprocating paper feeding means, aligning means for guiding paper webs to said feeding and printing means including guide rolls spaced at equal predetermined distances in the path of the paper webs from

the corresponding carriage means, and means including electrical contacts resiliently urged toward said guide rolls and normally spaced therefrom by paper webs passing therebetween for completing the circuit to initiate simultaneous stoppage of said prime mover and opening of said clutch upon occurrence of paper exhaustion. 5

24. In a printing machine, a prime mover, an operating electrical circuit therefor, a gear train operatively connected to said prime mover, a clutch in said gear train, a reciprocable paper feeding and printing carriage, means including a sprocket chain and connecting link for operating said carriage from said gear train, common means for simultaneously opening said operating circuit and said clutch latching means normally operative for latching said circuit and clutch opening means against operation, means responsive to paper supply exhaustion for releasing said latching means, and means on said connecting link made operable by release of said latching means to open said electrical circuit and clutch means.

25. In a printing machine, a prime mover, an operating circuit therefor, a gear train operatively connected to said prime mover, a clutch in said gear train, a reciprocable paper feeding and printing carriage, means including a sprocket chain and connecting link for operating said carriage from said gear train, common means for simultaneously opening said operating circuit and said clutch solenoid operated latching means normally operative for latching said circuit and clutch opening means against operation, means including a switch responsive to paper supply exhaustion for releasing said solenoid operated latching means, and means on said connecting link made operable by release of said latching means to operate said circuit and clutch opening means to simultaneously open the prime mover operating circuit and clutch for stopping said carriage at a predetermined point in its cycle of operation and prevent moving thereof due to "coasting" of the prime mover upon opening of its operating circuit. 30 35 40 45

CLAYTON E. WYRICK.
